UNITED STATES PATENT OFFICE.

IRVEN H. WILSEY, OF CHICAGO, ILLINOIS.

MEANS FOR AND METHOD OF FACILITATING REPAIR OF FABRICS.

Application filed April 25, 1927. Serial No. 186,335.

This invention relates to a novel method of and means for arresting and preventing the enlargement of holes or tears in fabric or like material and for facilitating the repair there-
5 of.

It is a well known fact that breakage of even a single thread in a knitted fabric, as for example, a silk stocking, results in a so-called "run" which rapidly traverses the full
10 length of the stocking from the point of rupture. These "runs" are unsightly and render the stocking unfit to wear by fastidious dressers. The initial break of the thread usually occurs while the stocking is being
15 worn and therefore repair of the break at the moment is usually impracticable. If the progress of the run can be arrested immediately or shortly after the break occurs, the damage can usually be localized in a small
20 area so that the extent of mending required when the stocking is removed from the wearer's limb can be minimized.

It is a general object of my invention to provide a novel means and method of arresting
25 the damage or rupture of a stocking while it is being worn and to facilitate the permanent repair of the damaged portion.

To this end I provide a temporary holding or arresting device which has the property
30 of engaging the fabric at or around the damaged area and which is easily insertable into the stocking to be placed in engagement with the fabric and to be held in such engagement by the tension of the fabric against the limb
35 of the wearer. I also provide a device which has fabric-engaging properties and a gap or slot to expose the damaged portion, the latter device being arranged to be applied to the stocking at or around the damaged area on
40 the opposite side of the fabric from the first-mentioned device, whereby the two devices cooperate temporarily in holding the fabric until the first mentioned device is removed. Thereupon the damaged portion of the fabric
45 will be exposed along the slot or gap in the second device so that the damaged portion may be easily mended by a suitable needle, crochet hook or the like while firmly supported in that position.

50 Referring to the drawings:

Fig. 1 is a plan view on an enlarged scale, of one embodiment of the invention showing the holding device in position on a piece of material.

55 Fig. 2 is a section taken on the line 2—2 of Fig. 1.

Figs. 3, 5, 6 and 8 are plan views of other forms of the invention.

Figs. 4, 7 and 9 are sectional views of the above taken on the lines 4—4, 7—7 and 9—9 of Figs. 3, 6 and 8, respectively.

Fig. 10 is a plan view of a means for facilitating repair.

Fig. 11 is a section of the same taken on the line 11—11 of Fig. 10.

While I have shown and will herein describe in detail several preferred embodiments of this invention, it is to be understood that I do not thereby intend to limit the invention to those specific forms disclosed but intend to cover all modifications and alternative constructions falling within the spirit and scope of the invention as expressed in the appended claims.

Generally, the preferred means for attaining a temporary mend or for arresting the progress of a run comprises a substantially invisible base which carries a plurality of small material engaging members. These members are adapted to engage or penetrate and hold the material about the broken thread or threads against strain or pull, which would tend to enlarge the hole. The base may be formed of any suitable material, either transparent, as celluloid, or colored to correspond to the color of the fabric to be reinforced, in which case the base may be formed of a suitable metal. The small material engaging members may be secured to the base or may be formed integrally therewith as desired and preferably project from the surface of the base at a slight angle thereto.

Referring to the drawings,

Figures 1 and 2 show one form of the invention in which the base is in the form of a substantially circular disk 15 having a plurality of small material engaging teeth 16 struck upwardly on one side thereof at a slight angle.

The form shown in Figs. 3 and 4 is similar to that of Fig. 1 except that the center of the disk has been removed to provide a base in the form of an annular rim 17 which has a plurality of teeth 18 formed on the inner edge of the rim.

Fig. 5 is substantially the same in construction as the form shown in Fig. 3, the annular base 19 in this instance being elongated to provide a means adapted to be used on longer tears.

In Figs. 6 and 7 a ring 20 formed of wire or the like supports the annular series of

material engaging teeth 21 of the same material. This type of support would, of course, be colored to correspond with the color of the fabric to be supported.

5 The modification shown in Figs. 8 and 9 comprises a suitable base 22 such as one similar to that employed in the form shown in Fig. 1, having a plurality of separately formed material engaging teeth 23 inserted 10 through and secured to the base.

Each of the modified forms above described are substantially the same in function, differing only in construction to adapt the supporting means to meet different requirements 15 as presented by different material and fabrics. The temporary supporting use of the device is shown in Fig. 1. When a tear or break 24 occurs in the fabric 25, the base of one of the devices is positioned immediately over the 20 hole in the fabric with the teeth on the device engaging the unbroken material thereabout. Preferably the device is applied upon the inner side of the fabric in which position only the small points of the teeth may be visible. In the case of a stocking, for example, the device is inserted in the stocking to engage the inner side of the fabric. In this 25 position the tension of the stocking holds the base of the device firmly against the wearer's 30 limb to prevent accidental disengagement of the teeth from the fabric. The teeth are arranged radially with respect to the break to resist any pull or strain on the fabric and hold the broken thread against any force 35 which would pull the thread to enlarge the hole or cause a run. Thus a temporary holding device is provided which may be applied to the fabric as soon as a rupture occurs or is noticed and which will remain in place to prevent 40 any further run or enlargement thereof until such time as a permanent repair can be made.

I have shown, in Figs. 10 and 11, a means to be used in conjunction with the temporary holding means, by which the material is held in the same manner as with the temporary means while a permanent repair of the break is made. In this instance this repairing means comprises a plate 26 having both ends 50 27 reversed upon itself to overlie one side thereof. The ends 27 stop short of the center of the plate to provide a gap 28 therebetween, and the surface of each end is provided with a plurality of small teeth 29 preferably 55 struck upwardly from the material.

When one of the temporary holding devices has been applied to the inner side of the material to stop a run and it is desired to mend the fabric, the stocking is removed from the 60 wearer and the teeth upon the repairing plate 26 are engaged in the fabric at the opposite side of the fabric, with the hole in the fabric

overlying the gap 28 while the temporary means is still holding the fabric. The temporary means is then removed and the hole 65 may be readily repaired in any suitable manner while the repairing means holds the fabric. Thus at all times during the transfer of the fabric from one device to the other, the temporary and the repair means cooperate 70 to prevent enlargement of the hole.

It will be apparent from the foregoing description that I have provided a simple and effective means for arresting the enlargement of a hole in a piece of material, and that I have further provided a means for facilitating the repair of such a hole which means cooperates with the temporary means in holding the fabric during the transfer of the material from one to the other.

I claim as my invention:

1. A temporary repair means for preventing the enlargement of holes in fabric comprising, in combination, a substantially invisible base and a plurality of small members 85 projecting therefrom adapted to engage the fabric about a hole therein to prevent the hole from being enlarged by strain.

2. A temporary repair means for preventing the enlargement of holes in fabric comprising, in combination, a base colored so as to be substantially invisible when used with a piece of fabric, and a plurality of sharp teeth projecting from said base adapted to be engaged in said fabric about a hole 95 therein to prevent enlargement of the hole.

3. A means for facilitating the repair of a piece of material comprising, in combination, a device having means engaging the material in each direction about a damaged portion thereon, and a second device adapted to engage the opposite side of the material from said first mentioned device, said second device having an opening therein to expose 100 said damaged portion for repair.

4. A means for facilitating the repair of a piece of material comprising, in combination, a temporary device including a plurality of material engaging means substantially grouped about a common point and engaging the material radially about a damaged portion thereof placed adjacent said point, and a repair device adapted to engage the opposite side of the material from said temporary device to hold said material when said temporary device is removed, said repair device including a plurality of material engaging teeth disposed about said device to provide a space free of teeth to permit a damaged portion positioned within said space to be repaired.

In testimony whereof, I have hereunto affixed my signature.

IRVEN H. WILSEY.
